DESIGN FOR A BOWL OR SIMILAR ARTICLE OF GLASSWARE

George Sakier, New York, N. Y., assignor to Fostoria Glass Company, Moundsville, W. Va.,
a corporation of West Virginia

Application December 14, 1933, Serial No. 50,071

Term of patent 7 years

To all whom it may concern:

Be it known that I, GEORGE SAKIER, a citizen of the United States of America, and resident of New York, county of New York and State of New York, have invented a new, original, and ornamental Design for a Bowl or Similar Article of Glassware, of which the following is a specification, reference being had to the accompanying drawing, in which—

The dominant feature of the design is the appearance of the form of handles depicted in the drawing.

I claim—

The ornamental design for a bowl or similar article of glassware as shown and described.

GEORGE SAKIER.
